[57] CLAIM

The ornamental design for a combined data and voice communication terminal, as shown and described.

DESCRIPTION

FIG. 1 is a front, left side perspective view of the combined data and voice communication terminal showing my new design;

FIG. 2 is a front, left side perspective view thereof with the monitor tilted and the handset removed from its cradle;

FIG. 3 is a front elevational view thereof on an enlarged scale, the monitor being tilted as shown in FIG. 2;

FIG. 4 is a front elevational view thereof on an enlarged scale, the monitor being upright as shown in FIG. 1; FIG. 5 is a top plan view thereof on an enlarged scale, the monitor being tilted;

FIG. 6 is a top plan view thereof on an enlarged scale, the monitor being upright;

FIGS. 7 and 8 are left side elevational views thereof on an enlarged scale, the monitor being respectively tilted and upright;

FIGS. 9 and 10 are right side elevational views thereof on an enlarged scale, the monitor being respectively tilted and upright;

FIGS. 11 and 12 are right side elevational views thereof on an enlarged scale, the monitor being respectively upright and tilted;

FIG. 13 is a bottom plan view thereof on an enlarged scale.
